PORTABLE VOLT-AMMETER OR THE LIKE

Takeo Kuramoto, 14-18 Higashigaoka 2-chome,
Tokyo, Japan

Filed Oct. 11, 1966, Ser. No. 4,232

Term of patent 14 years

(Cl. D26—1)

FIG. 1

FIG. 2

FIG. 3

FIG. 4

FIGURE 1 is a perspective front view of a portable volt-ammeter or the like, showing my new design;

FIG. 2 is a perspective rear view thereof;

FIG. 3 is a side view thereof, its lower portion shown in a turned position; and

FIG. 4 is a top plan view thereof.

The fragmentary showing of the carrying strap is for illustrative purposes only, the essential feature of the design being shown in full lines.

I claim:

The ornamental design for a portable volt-ammeter or the like, as shown and described.
